CLAIM

The ornamental design for a rotary actuator housing, as shown and described.

DESCRIPTION

FIG. 1 is a top perspective view of a rotary actuator housing showing my new design;

FIG. 2 is a left side elevation view of the rotary actuator housing;

FIG. 3 is a right side elevation view of the rotary actuator housing;

FIG. 4 is a rear elevation view of the rotary actuator housing;
FIG. 5 is a front elevation view of the rotary actuator housing;

FIG. 6 is a top plan view of the rotary actuator housing;

FIG. 7 is a bottom plan view of the rotary actuator housing; and,

FIG. 8 is a bottom perspective view of the rotary actuator housing.

The elements shown in broken lines are for illustrative purposes only and form no part of the claimed design.

The broken line(s) which define the bounds of the claimed design form no part thereof.
